APPARATUS FOR RIPPING RAW TOBACCO LEAVES

Oswald Erich Eissmann, Dresden, Germany, assignor to "Universelle" Cigarettenmaschinen-Fabrik J. C. Mueller & Co., Dresden, Germany

Application June 1, 1935, Serial No. 24,456
In Germany June 4, 1934

7 Claims. (Cl. 131—57).

This invention relates to ripping of the body portion of tobacco from the ribs of the leaves.

An object of this invention is to provide an apparatus whereby the compressed layers of leaves may be fed to a machine and the body or web portion of the leaves removed from the ribs.

Another object of this invention is to provide a machine of this character which is so constructed that the initially removed tobacco leaf portions are thrown about in a housing so that these loosened portions will be beaten by a rotary toothed beater which will operate to remove the web portion of the tobacco leaf from the ribs.

A further object of this invention is to provide in a device of this kind means whereby the retension of the loosened leaves may be controlled in the beating portion of the device by adjustable grate bars.

A still further object of this invention is to provide a machine of this character whereby the tobacco in its initial condition is compressed and fed to a separating member which carries the separated leaves to the beating drum for removal of the web portions of the leaf by the beating drum.

With the foregoing and other objects in view, the invention will be more fully described hereinafter, and will be more particularly pointed out in the claims appended hereto.

In the drawings, wherein like symbols refer to like or corresponding parts throughout the several views.

Figure 1 is a longitudinal section partly in detail through a machine constructed according to an embodiment of this invention.

Figure 2 is a front elevation of one blade of the toothed separating member.

Figure 3 is a fragmentary side elevation partly in section of the lower portion of the beating member.

Figure 4 is an enlarged side elevation partly in section of a modified form of heating means, and

Figure 5 is a sectional view taken on the line 5—5 of Figure 4.

Figure 6 is a sectional view of a modified form of the invention.

Referring to the drawings wherein like numerals of reference designate corresponding parts throughout the several views, the numeral 10 designates generally a housing of suitable size which is mounted on standards 13. The housing 10 is provided at one end thereof with an opening 11 forming an intake opening through which a conveyor 12 operates so as to convey the leaves of

tobacco to the housing 10 at the intake side thereof.

The conveyor 12 is operated in any conventional manner and in the present instance operates through a power member 14 which is disposed below the housing 10 and within the frame 13. The power member 14 is connected to the conveyor 12 by belts or the like as will be herein-after described.

A compression roll 15 is mounted on the shaft 16 journaled in the housing 10 and this shaft 16 has a gear 17 secured thereto. A shaft 18 is journaled in the housing 10 at one side of the shaft 16 and is provided with a pulley 19 over which a belt 20 travels. A gear 21 is secured to the shaft 18 and meshes with the gear 17 so that rotation of the gear 21 will effect rotation of the gear 17 and the pressure roll 15. If desired the inner end of the conveyor 12 may be operatively connected with the shaft 18. A webbing 22 is disposed between the inner end of the conveyor 12 and the periphery of the drum or pressure roll 15 so that the tobacco leaves moving with the conveyor 12 will pass to the upper portion of the pressure roll 15 which turns in the direction indicated by the arrow in Figure 1. A pair of pressure rolls 23 and 24 are secured to shafts 25 and 26 respectively which are journaled in the housing 10 and are connected as by a gear train 27 to the gear 17. The webbing member 22 is disposed between the two pressure rolls 23 and 24 and overlies the pressure roll 15.

A curved plate 29 is disposed forwardly of the pressure member 15 and has its rear end portion partly overlying the periphery of the roller 15 and this rear end portion is disposed in spaced relation to a bar 30 which is positioned adjacent the inner pressure roll 24 and the tobacco which is compressed between the rolls 15, 23 and 24 is fed between the space formed by the rear end portion of the plate 29 and the bar 30.

As the tobacco is forced between the rear portion of the plate 29 and the pressure bar 30 this tobacco in its compressed condition is torn away by means of a loosening member generally designated as 31. This loosening member 31 is mounted on a shaft 32 and a pulley 33 is secured to the shaft 32 and has a driving belt 34 trained thereover. A second and smaller pulley 35 is secured to the shaft 32 and the belt 20 is trained over this pulley 35.

The loosening member 31 is formed of a pair of opposed toothed plates 36 shown more specifically in Figure 2. These plates are secured to radially arranged arms 37 which are fastened to

the shaft 32. The teeth of the loosening member 31 swing closely adjacent the inner concave surface of the plate 29.

It will be seen that the inner concave surface 5 of the plate 29 is substantially concentric with the circular path of the tips of the comb prongs or toothed plates 36, and the plate 29 acts as an anvil to the tobacco moved along by the comb 36. The upper end of the plate 29 is provided with 10 an abutment 29^a in line with the webbing or abutment 22. The upper and lower rollers 17, 23 and 24, the member 28, bar 30 and abutment 29^a, suitably disposed from the abutment or bar 30, form a channel, which channel discharges 15 against the path of the tips of the combs 36, to enable the combs 36 to pull the leaf portions close by the abutment 29^a and along the inner contour of the plate or concave 29.

A beating drum or member 38 having beating 20 teeth 39 is mounted on the shaft 40 journaled in the housing 10 and the teeth 39 are so positioned as to engage between the teeth of the plate 36. In this manner when the loosening member 31 25 rotates as shown by the arrow in Figure 1 the beating member 38 will rotate in the direction shown by the arrow in Figure 1 and will rotate at a faster rate by reason of the belt 34 engaging a relatively small pulley 41 which is secured to the shaft 40. An idling pulley 42 is mounted on the 30 shaft 43 and one run of the belt 34 engages over the pulley 42.

Disposed below the beating member 38 there is 35 positioned a grate member 44 which is supported for adjustment toward or away from the beating member 38 by means of slotted arms 45. This grate member 44 comprises a plurality of spaced apart bars 46 which, as shown in Figure 1, are spaced apart at varying distances the distance between the bars increasing in the direction of 40 the rotation of the beating member 38.

The slotted arms 45 are held in adjusted position by means of headed bolts or adjusting members 47 which engage in horizontally disposed slots 48 carried by a bottom wall or frame piece 45 49.

When the loosened material drops through the grate bars 46 the material will fall onto a conveyor 50 which conveys the loosened material both web and ribs out of the housing 10. 50 A plate or hopper 51 is positioned inwardly of the housing 10 so as to prevent any loosened material dropping through the grate bars 46 from passing forwardly and to retain this loosened material on the conveyor 50 until removed 55 by movement of the conveyor.

In Figure 4 there is shown a modified form of 60 beating means wherein the beating member 38^a is disposed in a housing 10^a similar to the housing 10 and the grate member or screen 44^a is positioned concentrically below the beating member 38^a. In this modified form the grate bars 46^a are each separate one from another and are provided with right angularly related opposite end portions 52 through which bolts 53 extend. These 65 bolts 53 engage through radially arranged slots 54 provided in the housing 10^a. By means of the individual adjustment of the grate bars 46^a the desired retention of the material can be had for beating by the beating member 38^a. It will 70 be obvious that movement of the grate bars 46^a toward the drum or beating member 38^a will reduce the spaces between the grate bars and movement away from the beating member 38^a will enlarge these spaces.

75 In Figure 6 there is shown a further modifica-

tion of this invention where the housing 10^b has an improved form of tobacco loosening means in the form of a toothed member 36^b which is integrally secured to an arm 55. It will also be understood that in this modified form of separating means either of the drums shown in Figures 1 or 4 with the grate bars of Figure 4 may be used.

In the use and operation of this device the tobacco is fed to the housing 10 on the conveyor 12 and compressed between the rolls 15, 23 and 24. The compressed layers of tobacco leaves are loosened by the loosening member 31 which has the loosening blades 36 secured thereto. This loosened tobacco is then carried to the separating member 38 which turns at a faster rate than the loosening member 36. The teeth 39 of the separating member 38 will throw the tobacco toward the top of the housing 10 and as this tobacco falls down it will again strike the separating member 38 and after several beating operations the tobacco will be practically completely separated as to the web from the ribs.

In many instances the ribs R, as shown in Figure 3, will engage between the grate bars 46 and the web portions W will be torn off of the ribs R before the removed web portions are able to drop between the bars or screening members 46.

It is obvious that various changes and modifications may be made in the details of construction and design of the above specifically described embodiment of this invention without departing from the spirit thereof, such changes and modifications being restricted only by the scope of the following claims.

What is claimed is:

1. In an apparatus for ripping raw tobacco leaves, forwarding compressing means for conveying the leaves, an abutment disposed in relation to said means to form with said means a pressure channel, means for feeding tobacco leaves into said channel and between said forwarding compressing means, and loosening means at the outlet end of the channel acting upon the leaves resting on the abutment forming the channel for loosening the leaf portions from the ribs of the tobacco leaves, said means including comb prongs acting upon the compressed tobacco leaves perpendicularly to the plane of said leaves while under compression in said pressure channel for loosening the leaf portions from the ribs of the tobacco leaves.

2. In an apparatus for ripping raw tobacco leaves, forwarding compressing means for conveying the leaves, an abutment disposed in relation to said means to form with said means a pressure channel, means for feeding tobacco leaves into said channel and between said forwarding compressing means, means at the outlet end of the channel acting upon the leaves resting on the abutment forming the channel for loosening the leaf portions from the ribs of the tobacco leaves, said loosening means including comb prongs acting upon the compressed tobacco leaves perpendicularly to the plane of said leaves while under compression in said pressure channel for moving said leaves away from the pressure channel and straightening them out, and a plate having an interior contour concentric with the circle formed by the circular movement of the tips of said comb prongs, said plate extending below said abutment about a third of the arc of said circle, and acting as an anvil to the action of the prong tips on the tobacco leaves moved along the same, whereby the

tobacco leaves are straightened out and the leaf portions loosened from the ribs of the tobacco leaves.

3. In an apparatus for ripping raw tobacco leaves, having a housing, forwarding compressing means for conveying the leaves, an abutment disposed in relation to said means to form with said means a pressure channel, means for feeding tobacco leaves into said channel and between said forwarding compressing means, means at the outlet end of the channel acting upon the leaves resting on the abutment forming the channel for loosening the leaf portions from the ribs of the tobacco leaves, said loosening means including comb prongs acting upon the compressed tobacco leaves perpendicularly to the plane of said leaves while under compression in said pressure channel for moving said leaves away from the pressure channel and straightening them out, a plate having an interior contour concentric with the circle formed by the circular movement of the tips of said comb prongs, said plate extending below said channel about a third of the arc of said circle, and acting as an anvil to the action of the prong tips on the tobacco leaves moved along the same, a beater roll disposed at the outlet end of the loosening means and its plate, said beater roll having pins adapted to engage interstices of the comb prongs of the loosening means, strip off the ribs adhering to them, carry them along, and by beating the same against the housing, remove any leaf portions still adhering to the ribs, a grating concentric with the axis of rotation of the beater roll, one end of said grating extending in proximity to one end of the curved plate of the loosening means, and means adjusting the grating to and from the beater roll, said grating having rods spaced at different distances from each other, said distances increasing in size progressively in the direction of movement of the pins of the beater rolls, whereby the leaf portions are stripped from the ribs of the tobacco leaves.

4. In an apparatus for ripping raw tobacco leaves, having a housing, a pressure channel means for feeding tobacco leaves into said channel, means at the outlet end of the channel acting upon the leaves for loosening the leaf portions from the ribs of the tobacco leaves, said loosening means including comb prongs acting upon the tobacco leaves perpendicularly to the plane of said leaves while under compression in said pressure channel for moving said leaves away from the pressure channel and straightening them out, a plate having an interior contour concentric with the circle formed by the circular movement of the tips of said comb prongs, said plate extending below said abutment about a third of the arc of said circle, and acting as an anvil to the action of the prong tips on the tobacco leaves moved along the same, a beater roll disposed at the outlet end of the loosening means and its plate, said beater roll having pins adapted to engage interstices of the comb prongs of the loosening means to strip off the ribs adhering to them, carry them along, and by beating the same against the housing, remove any leaf portions still adhering to the ribs, whereby the leaf portions are stripped from the ribs of the tobacco leaves.

5. In an apparatus for ripping raw tobacco leaves, having a housing, a pressure channel means for feeding tobacco leaves into said channel, means at the outlet end of the channel acting upon the leaves for loosening the leaf portions from the ribs of the tobacco leaves, said loosening means including comb prongs acting upon the tobacco leaves perpendicularly to the plane of said leaves while under compression in

said pressure channel for moving said leaves away from the pressure channel and straightening them out, a plate having an interior contour concentric with the circle formed by the circular movement of the tips of said comb prongs, said plate extending below said channel about a third of the arc of said circle, and acting as an anvil to the action of the prong tips on the tobacco leaves moved along the same, a beater roll disposed at the outlet end of the loosening means and its plate, said beater roll having pins adapted to engage interstices of the comb prongs of the loosening means, strip off the ribs adhering to them, carry them along, and by beating the same against the housing, remove any leaf portions still adhering to the ribs, a grating concentric with the axis of rotation of the beater roll, one end of said grating extending in proximity to one end of the curved plate of the loosening means, and means adjusting the grating to and from the beater roll, said grating having rods spaced at different distances from each other, said distances increasing in size progressively in the direction of movement of the pins of the beater rolls, whereby the leaf portions are stripped from the ribs of the tobacco leaves.

6. In an apparatus for ripping raw tobacco leaves, having a housing, a pressure channel means for feeding tobacco leaves into said channel, means at the outlet end of the channel acting upon the leaves for loosening the leaf portions from the ribs of the tobacco leaves, said loosening means including comb prongs acting upon the tobacco leaves perpendicularly to the plane of said leaves while under compression in said pressure channel for moving said leaves away from the pressure channel and straightening them out, a plate having an interior contour concentric with the circle formed by the circular movement of the tips of said comb prongs, said plate extending below said channel about a third of the arc of said circle, and acting as an anvil to the action of the prong tips on the tobacco leaves moved along the same, a beater roll disposed at the outlet end of the loosening means and its plate, said beater roll having pins adapted to engage interstices of the comb prongs of the loosening means to strip off the ribs adhering to them, carry them along, and by beating the same against the housing, remove any leaf portions still adhering to the ribs, a grating concentric with the axis of rotation of the beater roll, one end of said grating extending in proximity to one end of the circular plate of the loosening means, means adjusting the grating to and from the beater roll, said grating having rods spaced at different distances from each other, said distances increasing in size progressively in the direction of movement of the pins of the beater rolls, said housing having radial slots, extensions on said grating rods movable in said slots, and means fastening the extensions in position in said slots, whereby the leaf portions are stripped from the ribs of the tobacco leaves.

7. In an apparatus for ripping raw tobacco leaves, having a housing, forwarding compressing means for conveying the leaves, superposed abutments disposed in relation to said means to form with said means a pressure channel, one end of each abutment being on a circle, means for feeding tobacco leaves into said channel and between said forwarding compressing means, means at the outlet end of the channel acting upon the leaves resting on the abutments forming the channel for loosening the leaf portions from

the ribs of the tobacco leaves, said loosening means including comb prongs acting upon the compressed tobacco leaves perpendicularly to the plane of said leaves while under compression in said pressure channel for moving said leaves away from the pressure channel and straightening them out, a plate having an interior contour concentric with the circumference formed by the circular movement of the tips of said comb prongs, said plate extending below said abutments about a third of said circumference, said plate acting as an anvil to the action of the prong tips

on the tobacco leaves moved along the same, and a beater roll disposed at the outlet end of said loosening means and its plate, said beater roll having pins adapted to engage interstices of the comb prongs of the loosening means to strip off the ribs adhering to them, carry them along, and by beating the same against the housing, remove any leaf portions still adhering to the ribs, whereby the leaf portions are stripped from the ribs of the tobacco leaves.

OSWALD ERICH EISSMANN.
